UNITED STATES PATENT OFFICE

116,431

DESIGN FOR A PAIR OF SPECTACLES

George P. Miller, Dover-Foxcroft, Maine

Application January 16, 1939, Serial No. 82,367

Term of patent 14 years

To all whom it may concern:

Be it known that I, George P. Miller, a citizen of the United States, residing in Dover-Foxcroft, in the county of Piscataquis and State of Maine, have invented a new, original, and ornamental Design for a Pair of Spectacles, of which the following is a specification, reference being had to the accompanying drawing, forming part thereof.

Fig. 1 is a front elevational view of a pair of spectacles showing my new design.

Fig. 2 is a plan view of the same, the essential features of the design reside in the configuration of the frames because of the way in which they are attached to the lenses.

I claim:

The ornamental design for a pair of spectacles, substantially as shown and described.

GEORGE P. MILLER.
